UNITED STATES PATENT OFFICE

HUGO THONET-DRECHSEL, OF VSETIN, CZECHOSLOVAKIA

PORTABLE TENT

Application filed September 16, 1931, Serial No. 563,155, and in Czechoslovakia August 5, 1931.

This invention relates to a new and improved tent intended in particular for use on automobile tours.

In accordance with the invention the tent, the interior of which can be subdivided into a plurality of separate chambers, consists of a framework or skeleton composed of U-shaped, preferably tubular, metallic members the ends of which are brought together and articulated to a compound shackle or tie-plate at each side, and of a bag-shaped canvas covering which forms the roof, sides, and floor of the tent when set up.

The main advantage of this tent consists in the fact that the U-shaped spreading members can be folded together and the canvas wrapped around the folded-up skeleton, so that given suitable dimensions of the skeleton, the folded-up tent can be stowed in a covering and fixed on an automobile in the manner of a foldable all-weather bonnet, or can be supported on the spare-wheels at the rear of the car and attached to small brackets on the back mudguards. By virtue of its construction, the tent provided by the present invention can be very easily set up and taken down, and in spite of its comparatively light weight is adequately roomy.

One form of the invention is illustrated, by way of example, in the accompanying drawings, in which:—

Fig. 1 is a view in elevation of the standing skeleton, with the canvas, side straps, and bottom straps removed.

Fig. 2 is an elevation taken at right angles to Fig. 1.

Fig. 3 is a plan view corresponding to Fig. 1.

Fig. 4 shows the skeleton alone, in the folded-up state.

Fig. 5 is an elevation at right angles to Fig. 4.

Fig. 6 shows the skeleton set up without side straps and ground straps, in perspective.

Fig. 7 shows the skeleton of the tent attached with the ground and side straps to the holding pegs.

Fig. 8 is an elevation taken at right angles to Fig. 7.

Fig. 9 is a plan elevation corresponding to Fig. 7.

Fig. 10 is a front elevation of the tent pitched.

Fig. 11 is an elevation taken at right angles to that of Fig. 10.

Fig. 12 is a perspective view of the tent.

Referring to the drawings, the tent will be seen to consist of a metal skeleton, the component parts of which can be held in the spread or open position by means of straps, and of a canvas covering 1. The metal skeleton consists of U-shaped members, preferably steel tubes 2, 3, 4, with their ends articulated on each side to a tie-plate 5, so that they can be folded apart. Between the middle parts of these bent members straps are stretched, between the main hoop 2 and the side hoops 3, 3 the straps 6, and between the latter hoops and the sanding hoops 4, 4 the straps 6'. These straps are so dimensioned that they are taut when the tent is set up. Suitable means can be provided for the independent tightening of these straps. The two standing hoops 4, 4 are held in position when the tent is standing by means of tension straps 7, 7' which can be connected up by means of spring-hooks or any other suitable means, and which can further be provided with means for independent tightening.

The entire skeleton together with the straps 6, 6' is enveloped by the canvas covering 1 which is formed like a bag of the tent covering proper and a floor part. A door 9 and ventilation openings 11 are provided in the front of the canvas covering, and celluloid windows 10 in the front and sides of the same. The door and ventilation openings can be closed from the inside by means of the known lightning fasteners. Vertically beneath the tie-plates 5 there are provided openings in the floor part of the canvas covering through which the side portions of the hoops 2, 3, 4 together with the tie-plates 5, when folded up, can be passed, after which the whole of the canvas covering can be wrapped around the middle portions of the hoops. These openings in the floor part of the canvas covering are likewise adapted to be closed by means of lightning fasteners.

when the tent is standing. Openings are further provided in the floor part for the tightening straps 7, 7', for the ground straps 13, and for the side straps 12.

5 The tent is set up as follows. After having been detached from the automobile and divested of its casing, it is stood up on the tie-plates 5, so that all the hoops stand upright, as shown in Figs. 4 and 5. The canvas covering is then unwrapped from the middle portion of the hoops, and the side portions of the hoops are threaded through the floor openings mentioned above. The side hoops 3, 3 and the standing hoops 4, 4 are then allowed to swing to the ground, whereupon the whole structure is laid over on its side. The tightening straps 7, 7', which project from the canvas covering 1, are then linked up by means of the spring-hooks 8, thus tightening 20 the straps 6, 6'. The canvas is freed from the tie-plates 5, and the main body of the tent is complete, lying on its side (see Fig. 2). The tent is then stood up on its base, after which the side straps 12, which are attached at one 25 end to the main hoop 2 (Figs. 7, 8, 9), are stretched and fastened at their other ends to the holding-down pegs 14. At the same time the canvas covering is drawn down over these side straps. The ground straps 13, 30 which are attached at one end to the middle portions of the standing hoops 4, 4, are likewise fastened at their outer ends to the pegs 14. The side strap 12 and ground strap 13 on the same side of the tent consist preferably 35 of a single strap on to which a ring is threaded which can be brought through an opening provided therefor in the canvas covering and fastened to the peg 14, in setting up the tent. The tensioning of these latter straps produces the side rooms B, B' of the tent which 40 can be used for sleeping. The driving of the above-mentioned pegs secures the tent rigidly in position.

On the inner side of the steel tubes and 45 straps there is provided a second wall or curtain of lighter canvas which lies parallel with the outer canvas and serves to separate the sleeping compartments from the main compartment of the tent. The tent is thus double-walled, and correspondingly well insulated against cold and damp.

In taking down the tent, the side and ground straps are first detached from the pegs 14. The skeleton is folded up in the 55 manner shown in Figs. 4 and 5. The side portions of the folded-up hoops 2, 3, 4, together with the tie-plates 5, are then passed through the openings in the floor part of the canvas covering, and the latter wrapped round the middle portion of the hoops. The 60 tent is then put into a watertight case, and secured to the automobile in the manner described above.

The main compartment A of the tent can 65 be equipped with an electric lighting device

15 (Figs. 1 and 2) the supply wires of which can be taken through the tubes to a switch, disposed e. g. on one of the tie-plates 5, and thence to a source of current, e. g. the accumulator of the car. The tent is protected 70 from being struck by lightning by having the middle portion of the standing hoops 4, 4 covered with insulating material, so that the entire tent is perfectly electrically insulated from the ground.

In order to insulate the tent more completely from ground moisture, the tent can further be pitched on a sheet of oilcloth or the like. The dwelling compartment A of the tent can be furnished as required with carpets and articles of furniture (table and chairs). There is sleeping room in the side compartments B, B' for two or three persons. The tent can also be set up with ease in the dark, and can also be pitched while it is raining without danger of water penetrating into the interior.

The purchasing price of the tent is comparatively low.

I claim:—

1. A tent frame comprising in combination a plurality of U-shaped hoops, tie plates at the ends of said hoops and having the ends of the hoops articulated thereto so as to enable the hoops to be swung apart to extend radially from the tie plates and to be folded together for transport and tension straps connected to the hoops intermediate the ends thereof for limiting the distance apart of each pair of adjacent hoops, said straps, on erection of the frame being capable alone of maintaining the hoops in proper spaced relationship to form a taut frame.

2. A tent frame comprising in combination a plurality of U-shaped hoops, tie plates at the ends of said hoops and having the ends of the hoops articulated thereto, so as to enable the hoops to be swung apart to extend radially from the tie plates, with one pair of hoops extending downwardly, one pair laterally and one hoop centrally disposed and extending upwardly from the tie plates, and to be folded together for transport, tension straps connected to the hoops intermediate the ends thereof for limiting the distance apart of each pair of adjacent hoops, said straps, on erection of the frame being capable alone of maintaining the hoops in proper spaced relationship to form a taut frame, side straps connected to the central hoop and ground straps connected to the downwardly extending hoops for anchoring the tent to the ground, said side and ground straps being adapted to be secured to tent pegs by their ends remote from the ends attached to the hoops.

3. A tent frame comprising in combination a plurality of U-shaped hoops, tie plates at the ends of said hoops and having the ends of the hoops articulated thereto so as

to enable the hoops to be swung apart to extend radially from the tie plates and to be folded together for transport and tension straps connected to the hoops intermediate
5 the ends thereof for limiting the distance apart of each pair of adjacent hoops, said straps, on erection of the frame being capable alone of maintaining the hoops in proper spaced relationship to form a taut frame,
10 said tension straps including straps secured at one end to the hoops of one adjacent pair and fastening means for connecting together the free ends of said straps and for tightening the straps to spread the hoops to the extent permitted by the other tension straps.
15 4. A tent frame comprising in combination a plurality of U-shaped hoops, tie plates at the ends of said hoops and having the ends of the hoops articulated thereto so as
20 to enable the hoops to be swung apart to extend radially from the tie plates and to be folded together for transport and tension straps connected to the hoops intermediate the ends thereof for limiting the distance
25 apart of each pair of adjacent hoops, said straps, on erection of the frame being capable alone of maintaining the hoops in proper spaced relationship to form a taut frame, said tension straps including straps secured
30 at one end to the hoops of one adjacent pair and spring hooks for connecting together the free ends of said straps and for tightening the straps to spread the hoops to the extent permitted by the other tension straps.
35 In testimony whereof I have signed my name to this specification.

HUGO THONET-DRECHSEL.
